UNITED STATES PATENT OFFICE.

MELVILLE E. PETERS, GEORGE H. FATH, AND ALBERT F. MILLER, OF DENVER,
COLORADO.

AUTOMATICALLY-OPERATING CLOSED-GAP BLANK-GUMMING CYLINDER.

1,226,994.

Specification of Letters Patent.

Patented May 22, 1917.

Application filed December 22, 1915. Serial No. 68,272.

To all whom it may concern:

Be it known that we, MELVILLE E. PETERS, GEORGE H. FATH, and ALBERT F. MILLER, citizens of the United States of America, residing in the city and county of Denver and State of Colorado, have invented a new and useful Automatically-Operating Closed-Gap Blank-Gumming Cylinder, of which the following is a specification.

10 Our invention relates to a new closed gap type of blank or label gumming cylinder for blank or label gumming machines; and the objects of our invention are:

15 To provide a blank gumming roller for blank feeding and gumming machines, having a hinged segment which normally forms part of its peripheral surface, and which is adapted to be automatically swung inward, thereby to form a gap in said cylinder, said 20 segment when closed preventing the adhesive material which is supplied to the cylinder from entering the interior of the cylinder.

25 Further, to provide a gumming cylinder for blank feeding and gumming machines, which is adapted to receive and gum blanks fed thereto, said cylinder having a hinged segmental strip which normally forms a part of its peripheral surface, and a spring for 30 normally holding said segment in such position, said segment being adapted to be automatically swung in to leave a gap or opening in the cylinder, and thereby to release or expose the end portion of a blank carried 35 around by said cylinder, whereby the said exposed end of said blank may be gripped by suitable mechanism and the blank removed from the cylinder.

40 We attain these objects by the mechanism illustrated in the accompanying drawings, in which:

Figure 1, is a vertical, longitudinal sectional view of a gumming cylinder constructed in accordance with our invention.

45 Fig. 2, is an end view of the same, the segment thereof being swung in to form a gap or opening in the periphery of the said cylinder. And

50 Fig. 3, is a similar view showing the segment in position to form a coöperating part of the peripheral surface of the cylinder.

Similar letter of reference refer to similar parts throughout the several views.

Referring to the drawings,—

55 The numeral 1 designates a blank gum-

ming cylinder embodying our present invention, which is an improvement over our blank gumming cylinder illustrated in our pending application Serial No. 30,147, filed May 25, 1915, for a blank gumming machine. 60

Our present gapped cylinder is provided with closed end flanges on its opposite ends on which hub portions 2 and 3 are cast through the axial center of which and of the cylinder its supporting shaft 4 extends. 65 This gap gumming cylinder is provided with a gapped opening 5 in its circumferential surface that extends entirely across its length and is preferably about two inches wide in a cylinder of about seven inches in diameter. This gumming cylinder is preferably made of brass, and on each end flange to one side of its shaft hub a boss 6 is formed, and a small shaft 7 is extended entirely across this cylinder and through and 70 beyond both flanges far enough to have mounted on and secured to its opposite ends rock arm extension members 8 and 9 which are securely fastened on it by pins 10. 75

These rock arms 8 and 9 are formed on the inner side of a curved plate 11 which we term a segment plate, as it forms a part of the circumferential shell of the gumming cylinder, and its outer curved surface is a true curved part of the circumferential surface of the gumming cylinder, as it is fitted tightly between the side edges 12 and 13 of the gap and is turned and machined and finished in a lathe as one integrally surfaced cylinder. 80 85 90

It is the function of this segment plate to recede into the interior of the cylinder and expose the gap in the cylinder and thus free the edge of the blank and expose its edge, in order that it may be gripped by suitable 95 finger grippers and be peeled off of the gumming cylinder, as will be presently described.

Consequently the coöperating edges of the gap and also of the segment plate must fit closely enough against each other to prevent any glue from working down into the interior of the cylinder through the side joints, and yet at the same time the joints must be so formed that the segment plate 100 will move down into the interior of the cylinder almost instantaneously at a predetermined point in each revolution of the gumming cylinder. 105

Consequently we have given to each edge 110

of the gap and to each similar edge of the segment plate, a different and special treatment. Thus the edge 13 of the gap is formed with a lower receding step portion which leaves the upper edge in the form of an overhanging lip, and the adjacent engaging edge of the segment plate is recessed in like manner, the lip 14 of the segment engaging the lip 13 of the gap of the cylinder. This leaves a clearance space between the edge 13 of the gap and the engaging edge 14 of the segment, which insures a tight fit at the surface of the cylinder.

The opposite edge 12 of the gap is provided with an under-cutting lip 15 and receding step portion 16, and the engaging edge 17 of the segment is curved to engage and fit the projecting lip, which moves up against it. The rock arm extensions of the segment permit it to swing inwardly on its pivotal shaft 7, and it is normally held in place against the edges of the gap by an expansive tension spring 23. This spring is mounted on a pivotal stem 19, which is provided with a flat shouldered head portion 20, that is pivotally mounted on a screw bolt 21, which extends through it and the bracket portion of the segment. The stem extends to and loosely through an abutment lug 22, that is pivotally secured to the adjacent end flange. There is one of these pivotal stems and one abutment lug at one end of the segment. The free end of this spring supporting stem works reciprocally and loosely in the lug 22, as the segment moves back into the cylinder and then out again into the gap, at a predetermined point in each revolution of the cylinder, as follows:

The segment is actuated to move into and out of the gap of the cylinder by a grooved cam 24, which is securely bolted by bolts to the inside of the adjacent side frame A. The cam engages a laterally projecting roller 25 that is secured to the free end of the extension rock arm 8 of the segment plate by a stud screw 26. The roller 25 projects beyond the adjacent end of the gumming cylinder into the cam, which is set so that as the gumming cylinder rotates the cam will engage the roller 25 at the proper time, and thus move the segment reciprocally throughout its length and against its spring.

Our present gapped blank gumming cylinder is adapted to be rotated between and work co-operatively with blank feeding and gumming rollers and a blank gripping transmitting and conveying cylinder and conveyer. We do not illustrate however any of these co-operating elements or the mechanism that rotates it, as it can be adapted to any blank gumming machine, and is illustrated in a new combination of blank feeding and gumming rollers and cylinders in our pending application Serial No. 68,270

filed December 22, 1915, for a co-operating blank feeding and gumming mechanism.

The operation of applying gum to a blank by means of our improved blank gumming cylinder, is as follows:

Our blank gumming cylinder is rotatively mounted and is adapted to be continuously rotated by any suitable mechanism, and it is provided with an operatively regulated adhesive gum distributing mechanism, and it receives blanks or labels from any automatically operating blank feeding roller; that particular roller we have illustrated and described in our pending application Serial No. 68,271 filed December 22, 1915, for a blank and label feeding roller for blank gumming machines is so relatively positioned to the blank feeding roller that it receives the advancing feeding edge of the blank on its segment plate, and as this plate as well as the whole surface of the cylinder is coated with gum, the blank sticks to it and is fed forwardly around and lies against and sticks to the gummed surface of the cylinder as it rotates, the feed roller being arranged to press the blank against the surface of the cylinder, which causes the blank to feed off from it onto the cylinder. The gumming cylinder carries the blank around with it to a predetermined point in its rotary movement, when the roller at the end of the extension of the rock-arm engages the cam 24, whereby the segment plate is moved inward and the end portion of the blank which rested on it is released and extends partially over the gap in the cylinder. Instantly thereafter, the exposed end of the blank is caught by automatically operating grippers, carried by an endless conveyer which passes over a transmission cylinder adjoining the gumming cylinder, and the blank is stripped from the gumming cylinder and deposited on the conveyer, whence it is conveyed to a suitable box covering machine. The transmission cylinder and the conveyer with its grippers are not illustrated, as they form no part of the present invention, and are mentioned only to convey an idea of how the blank is removed from the gumming cylinder. As the blank is stripped from the gumming cylinder, the cam 24 throws the segment 11 out to close the gap in the cylinder, and it is held in this position by the spring 23, until it is again moved inward by the cam to open the gap.

Having described our invention, what we claim as new and desire to secure by Letters Patent, is:

1. A hollow blank gumming cylinder provided with a gap extending throughout its length, and with flanged end portions adapted to axially support a shaft, a shaft secured in said end portions, a segment plate of the same circumferential peripheral curve as said cylinder fitting closely

enough into said gap to tightly fill and close the same, a rock shaft mounted within said cylinder parallel to said cylinder's supporting shaft, said segment plate being mounted on said shaft to swing reciprocally from the interior of said cylinder and close or open said gap, a roller provided lever on said plate and its supporting shaft, means including a grooved cam surrounding said roller for moving said segment into the interior of said cylinder to open said gap, and means including resilient means for moving said segment plate to normally close said gap after said gap has 15 being opened a predetermined period of time.

2. In a blank gumming cylinder, the combination with the side frames provided with bearings, of a shaft rotatively mounted on said bearings, a hollow blank gumming cylinder comprising a shell and shaft supporting end flanges secured on said shaft, means for rotating said cylinder, cams secured to said side frames adjacent to the opposite ends of said cylinder, a gap extending across said cylinder, a segment plate curved to register with the same curvature of said cylinder, and provided at one end portion with an arm, a hub portion on each arm intermediate of its ends, hub bearings formed on said shaft supporting ends of said gapped cylinder, a shaft extending through and secured to the hubs of said segment plates and pivotally journaled in the hubs of said cylinder's shaft supporting members and extending across said cylinder and segment plate, and

a roller at the end of said arm in engagement with the adjacent cam of said supporting frame.

3. In a blank gumming cylinder, the combination of the rotatable gapped blank gumming cylinder provided with flanged end portions at its opposite end portions, the segment plate closely fitting in and fitting said gap, said segment plate being provided with rock arm members at its opposite end portions pivotally secured in axial alinement with said cylinder's longitudinal axis, the cylinder supporting shaft, 45 the pivotal shaft pivotally connecting said segment to the interior of said cylinder to reciprocally move said segment plate to open and close said gap at predetermined points in each of said cylinder's revolutions, 50 the spring supporting pin pivotally connected to said segment at one end, the guide clip in which said pin is reciprocally and slidably mounted, the coiled expansive spring mounted on said pin and cam actuated means including a roller mounted on the end of said rock arm whereby said segment is moved into said cylinder to open said gap and said spring moves said segment to close said gap.

In testimony whereof we affix our signatures in presence of two witnesses.
